COMBINATION STORM SASH

Nicholas Ribaudo, Jr., Union City, N. J.

Application May 27, 1952, Serial No. 290,169

3 Claims. (Cl. 20—55)

1

This invention relates to a new improvement in combination storm sash of the type used with double hung windows, and particularly, it refers to improvements in construction of same attained by the use of resilient channels and molded frames, which are held in said resilient members and which do not require sash cords or other means to holding them in position.

This is a continuation in part of my patent application, filed Feb. 25, 1951, Serial No. 212,666, now abandoned.

The main object of this invention is to furnish a combination storm sash for use as a double insulating window in winter, and as a screen in summer, and which can be easily installed at low cost.

Another object of my invention is to provide a combination storm sash, in which the window can be quickly removed for cleaning.

Still another object of my invention is to provide a combination storm sash, which can be made readily at low cost from materials always available.

Other objects and advantages of this invention will be apparent during the course of the following description and claims.

In the accompanying drawing, forming a part of this specification, in which like numerals designate like parts throughout the same,

Figure 1 represents a front elevation of a window seen from inside, embodying my invention,

Figure 2 represents a section along line 2—2 in Figure 1,

Figure 3 represents a section taken at the meeting point of a double sash having a rail joint,

Figure 4 represents a section along line 4—4 in Figure 1,

Figure 5 is a section taken along line 4—4 in Figure 1, and is similar to Figure 4, except that it is taken with the screen in the lower position,

Figure 6 is taken along line 6—6 in Figure 1.

Figures 7—13 are variations of Figure 6, taken in the same place, but illustrating various positions of the storm sash and screen as will be hereinafter set forth.

In the drawing where for the purpose of illustration is shown a preferred embodiment of my invention, the numeral 10 designates the regular wooden frame of the window. A recess 11 in the wooden frame 10 provides a seat for the flexible resilient channel 12, which has two continuous grooves 13 and 14, in which the storm sash 15', and the screen 16, may be placed as indicated in Figure 1. The channel 12 is preferably a molded synthetic rubber product, which may be obtained

2

in long lengths and cut to size either at the time of installing the window or pre-cut as desired. The channels 12 are fastened to the window frame 10 by means of screws or nails 17, as indicated in Figures 2, 4, and 5.

In Figures 2 and 4 is also illustrated how the frame 15 is placed in a frame 18, which has a lip 19, which acts as a finger grip in raising or lowering the window. The screen 18, as illustrated in Figure 5, has a similar frame 20, which has the same lip 19, which is used as a finger grip, but which also has a groove 21 into which the screen is fastened.

The frames 18 and 20 may be made from aluminum, molded plastics or any other suitable materials, as desired. In cases where these windows are used as permanent ones the frames holding the glass 15' may be formed as shown in Figure 3, where the upper and lower frame join to make same draft and rain proof. The upper member 22, of the lower frame and the lower member 23, of the upper frame have tongues 24, which fit into grooves 25 for this purpose.

The lip 19 is only placed in the middle of the lower part of the frame for convenience in opening the window or closing same as mentioned above. This lip is of course not present on the sides and upper members of the frame as illustrated in Figure 2. In this manner the windows become adjustable as hereinafter described. An alternate construction is shown in Figures 6 to 13 where instead of tongues 24 fitting into grooves 25, the single tongue 24a fits into the recess or groove 25a.

In Figures 6—13 inclusive are illustrated the various positions of the glass and screen when same are taken out for cleaning. Figure 6 illustrates the normal position in which both glass panes are in the upper position and the screen 16 is in the lower position. This is the normal summer position with window open and fully screened. The channel 12 is slit in two places 25 and 26, as shown in Figures 6—13 inclusive and by means of these slits it is possible to remove the screen and glass as desired. To remove the screen 16, for instance, it is only necessary to push the tabs 27 in on both sides, as illustrated in Figure 7, whereupon the window 15' is pulled down through the resulting opening as illustrated in Figure 8.

Figure 9 shows the condition after the window 15' has been removed as described above. If it now should be desired to remove the screen, the same is first pushed down as indicated in Figure 10, whereupon the tabs 27 are pulled out and

the screen 16 is pulled outwardly and upwardly into the empty channel in channel 12, as indicated in Figure 11.

When the screen 16 is pulled all the way up in the second groove of channel 12, the tabs 27 and 28 are pushed back in place and the screen may now be used in the second groove if so desired. If on the other hand, the screen is to be removed, the tab 27 is pushed in as shown in Figure 13, and the screen 16 is removed exactly in the same way as described above for the window 15. In this manner, it is possible to place the window and screen in any desired position in any one of the two grooves in channel 12. The screen and the windows are easily removable for cleaning purposes, which is highly desirable in the normal use of such windows.

The operation of my invention is obvious from the above description and except for the removal of the screen or window frames, the operation is not different from that of any standard double hung window. It is thus possible to use these windows as storm windows or primary windows if so desired.

It is to be understood that the form of my invention, herewith shown and described is to be taken as a preferred example of same, and that various changes in the shape, size and arrangement of parts, may be resorted to, without departing from the spirit of my invention, or the scope of the subjoined claims.

Having thus described my invention, I claim:

1. A combination window of the character described comprising a resilient channel member being fastened around a window, said member having two parallel channels arranged to run all around said window, said channels having a plurality of slits located at the point where the

upper and lower sash meet when in closed position, and a plurality of glass and screen sash insertable through said slits whereby said sash are slidable in said channels.

5. 2. A combination window of the character described comprising a resilient channel member being fastened around a window frame, said member having a plurality of parallel channels arranged to run all around said window, said channel having a plurality of slits placed on both sides of said window located at the point where the upper and lower sash meet when in closed position, and a plurality of glass and screen sash insertable through said slits whereby said sash are slidable in said channels.

10 3. A combination window of the character described comprising a plurality of glass and screen sash, and a resilient channel member fastened all around inside of a window frame, said resilient channel member having a plurality of parallel channels and angular slits in the walls separating said channels and in the outer wall of

15 said member, said slits being located at the point where the upper and lower sash meet when in closed position whereby said glass and screen sash are slidable in said parallel channels and removable from same as desired.
